ALARM MEANS

George D. Pease, Cedar Rapids, Iowa

Application April 7, 1939, Serial No. 266,516

4 Claims. (Cl. 116—105)

This invention relates generally to signalling devices and in particular to an excess temperature alarm device.

It is a general object of my invention to provide a self contained cartridge type of alarm device for attracting attention when the temperature at the location of the alarm reaches a predetermined danger point.

It is another object of my invention to provide such a device as will indicate the general location of such excess temperature or danger point.

It is a further object of my invention to provide a device of this character which may be handled and shipped with complete safety.

It is a still further object of my invention to provide a device that is simple in construction and inexpensive to manufacture and maintain.

An additional object of my invention is to provide a signalling device in a cartridge form, so constructed as to be tamper-proof and so low in cost that such cartridges may be discarded after having fulfilled their purpose.

Other and further features and objects of the invention will be more apparent to those skilled in the art upon a consideration of the accompanying drawing and following specification, wherein are disclosed several exemplary embodiments of the invention, with the understanding, however, that such changes may be made therein as fall within the scope of the appended claims, without departing from the spirit of the invention.

In said drawing:

Figure 1 illustrates, in perspective, a cartridge type excess temperature signalling device constructed in accordance with one embodiment of my invention.

Figure 2 illustrates, in section, the construction of the device shown in Figure 1.

Figure 3 is a modified form of the structure shown in Figure 2.

Figure 4 is a sectional view of a tamper-proof type of cartridge as constructed in accordance with another modification of my invention, and

Figure 5 is a view in perspective, in enlarged relation, of the safety device and fusible plug of the device shown in Figure 4.

Figure 6 is a view in section of a modified means for supporting the shell within the end of the cartridge.

Figure 7 is an enlarged view of the tapered opening in the end of the device shown in Figure 4.

Referring now more particularly to Figures 1 and 2, one embodiment of my invention includes

in general a cartridge type of structure having a barrel indicated generally at 10 adapted to hold, at one end, a blank cartridge such as a blank shotgun shell or the like, as indicated at 11. At detonator pin 12 within the barrel and extending lengthwise thereof is biased strongly in the direction of the detonator cap of the shell by spring means, indicated generally at 13.

In the device shown the barrel 10 may be of any suitable material such as metal or fiber having a rim insert or flange member 14 inset in one end thereof to snugly receive the shell or blank cartridge 11. The opposite end of the barrel 10 may be threaded, as at 16, to removably receive a cap 17.

The detonator pin 12 may be cylindrical in form if desired, but is preferably flat at the portion 12a which extends through an opening 17a in the cap. The flattened portion of the pin is provided with two openings, one at 18 through which a fusible key 19 is inserted to hold the detonator pin ready to fire. This key may be made of any fusible alloy with a low melting point suitable for the purpose intended. Fusible alloys such as those known as "Lipowitz's" or Woods metal may be used when a very low temperature alarm is desired.

The compression spring 13 is positioned within the barrel with one end bearing against the cap 17 and the other end bearing against the washer or cup-shaped member 21 which is retained on the detonator pin near the inner end by means such as a pin 22.

It is preferable that the end of the detonator pin be made conical in shape to provide a small contacting area 12b.

The barrel may be provided with a strap member such as indicated at 23 to permit supporting the device in the desired location. The strap member may be spot welded or otherwise fastened, as at 24, to the barrel and may be provided with openings 26 through which nails or screws may be inserted.

It is apparent that one or a plurality of these devices may be used for fire protection for buildings. It is preferable that they be located at scattered points around the building. Since heated air rises, it is of course apparent that they will serve their purpose best if they are located at the high points in a building, such as in the peak of a roof or above any combustible materials, or near the ceiling in basements where combustible materials are stored.

In operation, the presence of heat in excess of the melting point of the key member 19 serves

to melt that member, permitting the spring to snap the detonator pin against the detonator cap of the blank cartridge 11. This cartridge may be filled with regular powder or may be filled with a mixture of regular powder and magnesium powder or the like to provide a bright flash as well as an explosion to locate the danger point. The cartridge may of course be provided with a slower burning illuminating means such as magnesium ribbon or the like to cause a flare rather than a flash of light.

A shield 25 may, if desired, be formed of light gauge metal with a plurality of slits or perforations 25a for prevention of injury to nearby persons. The shield may be slipped on the end of the body 10 and held in place by welding, pins or other means.

The flat portion of the detonator pin is provided with another opening 19b through which a pin or cotter key 19c may be installed while handling and during shipping to prevent premature explosions.

I preferably provide a felt or other type of insulating washer as shown at 20 to minimize the conduction of heat away from the fusible key. This permits the rapid response of the safety device to temperature changes. The small body of the key absorbs radiant heat quickly as compared to the large body of the barrel.

The threaded cap permits the recharging the device with a fresh cartridge and with a new fusible key.

The modified form of my invention illustrated in Figure 3 utilizes a firing pin which may be stamped from a flat sheet of metal rather than built up of a rod and washers and like materials. This modified form of the detonator pin, as indicated generally at 30, includes a portion 31 of a size to loosely fit in the opening 17a in the cap. This portion may be enlarged as at 32 to form the main body of the pin enclosed within the spring 13. Hook-shaped projections 33 extend beyond the body portion 32 so as to receive the end of the spring in place of the washer shown at 21 in Figure 2. The end of the pin is tapered down to a firing point 34. Openings 36 and 37 are provided in the same manner as the embodiment shown in Figure 2 for the reception of the fusible key member 38 and a cotter key or other safety locking device.

The embodiment of my invention illustrated in Figure 4 is directed particularly to a "throw-away" type of cartridge constructed so as to be tamper-proof. The main barrel of the device may be constructed of a light tubular material such as indicated at 41, formed or flared inwardly as indicated at 42 to form a restricted or tapered opening 43 through which the detonator pin 44 extends. The washer means 46 may be retained on the firing pin in any suitable manner as by a locking washer 47 snapped on a recessed portion 48 of the pin.

The firing pin may be held in the "cocked" position by means of a small block 49 of fusible metal keyed into the shaft as at 51 and adapted to jam within the restricted opening of the barrel at 43. It is apparent that melting of this plug will release the firing pin. The lower end of the barrel, as at 52, may be received within and fastened by means such as welding, within a short lower barrel 53. A plug member 54 is received within this lower barrel and adapted to rest against the lower end of the barrel 41. An opening 56, extending through the plug which may be of metal or any other suitable material,

serves as a guide for the firing pin. The detonator cap of the shell is aligned with the outer end of the opening 56, the shell being supported in position by means of a collar 57 which fits snugly over the cartridge and within the lower barrel 53. The outermost end of the barrel is rolled over this collar, as indicated at 58, to hold all parts in their proper position and to seal the device against tampering.

10 The outer end of the firing pin may be provided with an opening as before described for the insertion of a pin safety means. It is preferable, however, that the tamper-proof type of cartridge be provided with a safety means such as indicated generally at 60 and as more fully disclosed in Figure 5. In this construction the outermost end of the shaft at a point close to the fusible plug is flattened to provide an enlarged section 61 to prevent its passing through the constricted opening 43 in the end of the barrel. This prevents the firing pin from being accidentally released during shipping or installation. Slots are provided on either side of the pin just within the enlarged portion, as indicated at 62, leaving only a thin section 63 which may be snapped in two with a pair of pliers after installation. The removal of this safety head helps to eliminate tampering and attempts to refill the cartridge.

I have shown in Figure 6 a means for clamping the explosive shell within the end of the cartridge construction shown in Figure 4. The shell 41 is rolled or beaded inwardly as at 66 to form a shoulder. After the shell is in place the end 35 of the shell 41 is rolled over the shoulder of the shell, as at 67, to hold it in place and eliminate the collar members 54 and 57 and in fact eliminate the necessity for the lower barrel 53.

It is apparent that I have provided a device 40 for the indication of dangerous temperatures and one which may be adapted to a wide variety of uses, which is simple and positive in action, and which may be constructed very inexpensively. The light from successively exploding alarm devices will guide firemen to the fire source.

I have further devised a structure of a type 45 that will discourage tampering and attempts at refilling after having once been used.

Although I have described specific embodiments 50 of my invention, it is apparent that modifications thereof may be made by those skilled in the art. Such modifications may be made without departing from the spirit and scope of my invention as set forth in the appended claims.

55 I claim as my invention:

1. In a device of the type described and having a barrel with a restricted opening through the end thereof, a firing pin extending through the opening and fusible means for releasing the firing pin at a predetermined temperature, a safety means on the firing pin to prevent premature explosion comprising a flat and enlarged portion on the outermost end of the firing pin to prevent the said outermost end from passing through the opening, and cut-away portions in the sides of the pin adjacent to the enlarged portion so that the enlarged portion can be snapped off after installation of the device.

2. In a device of the class described, a tubular shell closed at one end and open at the other, means for holding a cartridge in the open end, a plunger extending through the closed end, means for guiding the plunger within the tubular shell, means for biasing the plunger toward the cartridge to fire it, the plunger having a recess

therein positioned so it is outside the shell when the plunger is retracted, and low melting point alloy metal located within the recess for bearing against the outside of the closed end for holding the plunger in retracted position against the biasing effect of the spring until an ambient temperature is reached at which the metal melts to permit the plunger to be driven against the cartridge, and the outer end of the plunger being flattened whereby the flattened end prevents the plunger from striking the cartridge as long as the flattened end is present, the plunger being partially cut away near the flattened end to permit the flattened end to be broken away to render the device operative when it has been installed.

3. In a cartridge type excess-temperature alarm, a tubular shell formed at one end to provide an inwardly tapering opening, means at the other end of the barrel for non-removably supporting in fixed position an explosive cartridge, a detonator pin contacting the detonator cap of the explosive cartridge, when released, and extending through the tapering opening first mentioned, a coil spring under compression, one end of same bearing against the inner surface of the barrel at the end thereof first mentioned, the other end of the spring engaging the detonator pin, and means for holding the detonator

pin in cocked position comprising a block of fusible metal keyed into the side of the detonator pin and jamming within the tapering opening in the barrel.

- 5 4. In a cartridge type, excess temperature alarm device, a tubular barrel, means comprising a rim rolled on the end of the barrel for supporting an explosive cartridge, the base of the cartridge resting inside the barrel and against the rim, other means bearing against the flat portion of the base of the cartridge to prevent movement thereof longitudinally of the barrel, a detonator pin within the barrel, means for guiding the end of the detonator pin adjacent the base of the cartridge, spring means within the barrel for biasing the detonator pin toward the cartridge, the barrel being constricted at the end opposite the cartridge to engage the adjacent end of the spring means and to closely receive the detonator pin, the wall of the opening, thus formed, tapering inwardly toward the detonator pin, and a plug of a fusible alloy secured to the detonator pin at a point outside the barrel whereby the spring means will jam the fusible plug in the tapered opening and whereby the possibility of the fusible plug becoming accidentally sheared off through jarring is greatly lessened.

GEORGE D. PEASE.
